UNITED STATES PATENT OFFICE.

CHARLES W. RODECKER, OF MARYVILLE, ASSIGNOR, BY DIRECT AND MESNE ASSIGNMENTS, TO HIMSELF, AND WILLIAM H. JAMES, OF ST. JOSEPH, MISSOURI, AND W. A. CORMACK, OF CHERRY VALE, AND A. I. STAGGERS, OF SALEM, KANSAS.

WINDOW-SCREEN.

SPECIFICATION forming part of Letters Patent No. 507,755, dated October 31, 1893.

Application filed April 15, 1892. Serial No. 429,249. (No model.)

To all whom it may concern:

Be it known that I, CHARLES W. RODECKER, of Maryville, Nodaway county, Missouri, have invented certain new and useful Improvements in Window-Screens, of which the following is a full, clear, and exact description, reference being had to the accompanying drawings, forming a part hereof.

My invention relates first to screens for the windows of dwellings, business-buildings, and various other similar structures, and secondly to the sashes of such windows, and the objects of my invention are, first, to produce window-screens which shall be simple, strong, durable and inexpensive in construction, and entirely automatic in their operation, and which shall be capable of application to all types of windows, and which shall be automatically extended and concealed in consequence of the raising and lowering of the window-sashes, and which, furthermore, shall in no way cause any disfigurement or material alteration in the structural features of the window frames or sashes; secondly, to produce attachments for window-sashes which shall prevent the entrance of insects, dust, or other objectionable matters into the apartments, and which shall be capable of application to all types of window-sashes, and which shall, furthermore, be simple, strong, durable, and inexpensive in construction.

To the above purposes my invention consists in certain peculiar and novel features of construction and arrangement, as herein-after described and claimed.

In order that my invention may be fully understood, I will proceed to describe it with reference to the accompanying drawings, in which—

Figure 1 is an inner side elevation of a window frame and its sashes with my improvements applied thereto. Fig. 2 is a transverse vertical section of the same, on the line 2—2 of Fig. 1. Fig. 3 is a horizontal section of the same, on the line 3—3 of Fig. 1. Fig. 4 is a detached perspective view of one of the screen-winding-rollers, its supporting-brackets, and a portion of one of the screens. Fig. 5 is a longitudinal section of the same, on the line 6—6 of Fig. 4; the roller-actuating spring being shown as partly broken away.

In the said drawings, 1 designates the frame or casing of a window, said frame or casing

being shown as of the usual rectangular form, and 2 designates the lower and 3 the upper sash of the window; these parts being (excepting as hereinafter explained) of the usual or any preferred form and type of construction.

4 designates a spring-rotated roller which is mounted horizontally in the window-casing just above the sill 5 thereof, and which is of hollow cylindrical form, and of such length as to extend from one groove to another in which the lower window-sash 2 works. At one end this roller carries a cap 6 which is riveted or otherwise secured upon the end of the roller 4, and from the middle of which extends a stud 7; the outer end of said stud being inserted into a bearing-opening 8 which opening is formed in the lower part of a vertical bracket 9. This bracket 9 is secured upon the sill 5 at a point adjacent to the wall of one of the grooves in which the lower sash 2 works. Longitudinally through this roller 4 extends a rod 10 which is of such length as to extend from near the cap 6 to and through the opposite end of the roller. The outer end 11 of this rod is flattened as shown and projects through a disk 12 so as to rotate freely in said disk. From the inner side of this disk project inwardly two flanges 13 which are inserted into notches in the corresponding end of the roller 4, thus preventing the disk from turning independently of the roller. Two external shoulders 14 and 15 abut respectively against the inner and outer sides of the disk 12 and thus retain the rod in its proper position without interfering with the free rotation of the roller 4. The flattened outer end 11 of the rod 10 enters a recess 16 in a companion bracket 17, the said bracket being secured in vertical position upon the sill 5 adjacent to the opposite groove from that occupied by the standard 9.

In order to prevent all possibility of accidental detachment of the flattened end 11 of the rod 10 from its bearing in the recess 16, a pivoted stop 18 is preferably secured upon the outer side of the bracket 17, and when in normal position, depends across the outer end of the recess, and also abuts against a stud 19 which also projects from the outer side of the bracket. Thus the stop or guard 18 may be raised when the end 11 of the rod is being inserted into the recess, and then al-

lowed to drop so as to close the outer end of the recess and thus retain the end 11 within said recess, the end 11 of the rod being moved to the inner end of the recess of course, to allow 5 the pivoted latch to clear or pass said end 11, in its descent. A coiled spring 20 surrounds the rod 10 and its inner end 21 is inserted into a transverse groove or notch which is formed in the inner end of the rod 10, while the outer end of said spring is suitably secured to the inner side of the disk 12. Thus when the roller 4 is rotated in one direction, the spring 20 is wound, and when the roller is released, the spring automatically 10 unwinds and rotates the roller 4 in the reverse direction. A collar or cap 22 is riveted or otherwise similarly secured to the corresponding end of the roller 4, as shown.

23 designates the lower screen section, the 20 lower margin of which is suitably secured longitudinally upon the roller 4, and which is of a width corresponding to that of the lower sash 2. At its upper margin, this screen-section is provided with a binding-strip 25 24 the ends of which are bent inward so as to enter recesses 25 which are formed in the lower corners of the inner sides of the sash 2; the arrangement being such that the ends of the binding-strip and the screen-margins 30 shall fit snugly between the inner side of the sash and the inner bead of the window frame or casing 1. Three, or any suitable or preferred number, of loops 26 of wire or other suitable material, are secured to the binding-strip 35 24 and are engaged with a corresponding number of nails 27, or equivalent devices, which are driven into the lower rail of the sash 2. A semi-cylindrical shield or guard 28 is secured to the sill 5 and extends upward and 40 outward so as to conceal the lower roller 4 and its attachments; said shield being of sheet-metal, or other suitable material, and corresponding in length with the width of the lower sash 2.

45 From the above description, it will be seen that when the loops 26 are connected to the nails 27, the lower screen-section 23 will be unwound from the roller 4, as the lower sash 2 is raised; this unwinding of said screen-section rotating the roller 4 so as to wind the spring 20. When the lower sash 2 is lowered, the spring 20 will unwind and consequently the lower screen-section 23 will be wound upon the roller 4.

55 In the upper part of the window-frame 1 just above the top-rail 29 thereof, is mounted horizontally a second roller 30 to which is attached the upper margin of the upper screen-section 31. This roller 30 in all respects is 60 the same as the roller 4 above described, and is also provided with caps 6 and 22, a rod 10, spring 20, and the other attachments the same as said roller 4; the ends of the binding-strip 24 of this upper screen-section and the margins 65 of said screen section, working between the inner bead of the upper sash 3 and said sash, as before described. Thus it will be

seen that when the upper sash 3 is lowered, the upper screen-section 31 will be unwound from the roller 30; winding the spring 20 of 70 said roller. When the upper sash 3 is raised, the spring 20 of the upper sash will be unwound and will so rotate the upper roller 30 as to wind the screen-section 31 thereon. Consequently, in both the upper and lower 75 sashes, the opening which is formed by raising or lowering the sashes is covered by the screen-sections, and all insects are excluded from the apartment. The upper roller 30 is usually concealed from view by the usual 80 window-curtain, but if desired, a shield or guard 28 (similar to the shield or guard 28, above described) may be used to conceal said upper roller, as indicated in dotted lines in Fig. 2. In order to exclude dust, dirt, and 85 insects from the room, a flexible strip 32, such as rubber or the like, may be secured to the upper bead 33 of the window-easing, and extend outward over the roller 30, so as to close the space between the roller 30 and the top-rail of the window-frame. In order to further prevent the entrance of dust, insects, &c., into the apartments, a strip 34, also of 90 flexible material, is secured to the under surface of the lower rail of the upper sash, and 95 the inner margin of said strip abuts closely against the outer surface of the pane of glass in said sash, so as to rub closely upon said pane when the sashes are moved.

From the above description it will be seen 100 that I have produced attachments which are simple, strong, durable and inexpensive in construction, and capable of application to all types of windows without involving any material structural alteration of the same, 105 and which may be readily applied and removed, as desired.

Having thus described my invention, what I claim as new therein, and desire to secure by Letters Patent, is—

110 In a roller for screen-windows, comprising a hollow cylindrical body-portion 4, a rod 10 extending longitudinally in said body-portion and a spring spirally surrounding said rod and secured thereto at one end, the combination 115 of a cap 22 secured upon one end of the roller, and having an inwardly extending flange at its outer end and a disk 12 mounted loosely upon the said rod 10 and bearing against the inner side of the cap 22 and 120 against the inwardly extending flange thereof, and having inwardly extending flanges 13 adapted to engage recesses in the end of the body-portion 4, of the annular shoulders 14 and 15 bearing upon the inner and outer 125 sides of the disk 12, to retain said rod in its proper position longitudinally, substantially as set forth.

130 In testimony whereof I affix my signature in the presence of two witnesses.

CHARLES W. RODECKER.
